G. C. TAFT.
COPYING-PRESS.

No. 178,204.

Patented May 30, 1876.

UNITED STATES PATENT OFFICE.

GEORGE C. TAFT, OF WORCESTER, MASSACHUSETTS, ASSIGNOR OF ONE-HALF
HIS RIGHT TO JONATHAN LUTHER, OF SAME PLACE.

IMPROVEMENT IN COPYING-PRESSES.

Specification forming part of Letters Patent No. 178,204, dated May 30, 1876; application filed
December 18, 1875.

To all whom it may concern:

Be it known that I, GEORGE C. TAFT, of the city and county of Worcester, and State of Massachusetts, have invented certain new and useful Improvements in Portable Letter-Copying Presses; and I do hereby declare that the following is a full, clear, and exact description of the same, reference being had to the accompanying drawings, which form a part of this specification, and in which—

Figure 1 represents a front view of my improved portable copying-press. Fig. 2 represents a plan view of the same. Fig. 3 represents a vertical section at line α α , Fig. 2. Figs. 4 and 5, 6 and 7, and also Fig. 8, represent modifications of the fastening and clamping device.

The object of my invention is to provide a light and compact copying-press for library or traveling use, which shall be simple in its construction and convenient of operation. To this end my invention consists in an improved copy-press composed of two rectangular plates, connected at their edges by hinges, and provided at their opposite edge with a pressure-clasp or clamp device, said clamps and hinges being capable of adjustment, to increase or diminish the space between the plates, and thus adapt the press for use with books of different thickness.

In the drawings, A and A' denote the lower and upper leaves or parts of the press, each of said parts, in the present instance, consisting of a thin rectangular plate provided with a strengthening flange or rib, a, its edge or border. These plates are preferably made from malleable iron or other metal; but wood panels with metal borders may be used, if desired, or any other suitable construction employed. B indicates the hinges by which the plates A A' are connected to each other at their rear edges, so that the upper plate can be turned up or folded back in the manner of a book-cover or box-lid. The hinges B are

made adjustable by the thumb-nuts B¹ working on the screw-spindles B². (See Fig. 3.) C indicates the clamp mechanism for forcing the plates together and imparting the necessary pressure. Said device consists of a loop, hung by the hinge-pin c to plate A, so as to swing up and back, and having a jaw, C¹, which can be forced down upon the top plate A' by means of the screw C², operated by the key or handle D, thus compressing the copy-book E, which is placed between the plates A A', as indicated in Figs. 1 and 3.

The clamp device and the hinge may be somewhat modified in construction, if desired, without changing the nature of my invention, and in Figs. 4, 5, 6, 7, and 8 I have shown three modifications of the clamp mechanism, all equivalent in their action with that illustrated in Fig. 3.

It will be observed that the size and weight of my improved copy-press are such that it can be transported in a valise or trunk without inconvenience, or it can be readily placed in the drawer of a writing-desk or table, thus rendering it a desirable article for use by travelers, or in private dwellings and libraries.

Having described my improved portable letter-copying press, what I claim therein as new and of my invention, and desire to secure by Letters Patent, is—

1. A portable copying-press, consisting of upper and lower leaves or plates A A', connected to each other by an adjustable hinge or hinges, and provided with an adjustable pressure-clasp or clamping device, substantially as set forth, and for the purposes stated.

2. The combination, with plates A A', of the screw-and-nut hinges B, hinged clasp C, locking-jaw C¹, and pressure-screw C², substantially as shown and described.

GEO. C. TAFT.
